UNITED STATES PATENT OFFICE.

AUGUSTUS B. FELGEMAKER, OF ERIE, PENNSYLVANIA.

PIPE-ORGAN.

SPECIFICATION forming part of Letters Patent No. 626,415, dated June 6, 1899.

Application filed August 27, 1898. Serial No. 689,653. (No model.)

To all whom it may concern:

Be it known that I, AUGUSTUS B. FELGEMAKER, a citizen of the United States, residing at Erie, in the county of Erie and State of Pennsylvania, have invented certain new and useful Improvements in Pipe-Organs; and I do hereby declare the following to be a full, clear, and exact description of the invention, such as will enable others skilled in the art to which it appertains to make and use the same.

This invention relates to pipe-organs; and it consists in certain improvements in the construction thereof, as will be hereinafter fully described, and pointed out in the claims.

The invention is illustrated in the accompanying drawings as follows:

Figure 1 shows a plan view of the air mechanism immediately adjacent to the pipes, the pipes being removed. Fig. 2 shows a section on lines 2 2 in Figs. 1 and 3. Fig. 3 shows a section on the lines 3 3 in Figs. 1 and 2. Fig. 4 shows an enlarged view of the pipe-valve. Fig. 5 shows a cross-section of said valve.

A marks the pipes, B the air-chamber below the pipes, and C the port-chamber between the pipes and the air-chamber B.

The air is admitted from the register-stops through the opening b to the chamber B, passes through the port c', through the valve E into the port-chamber c² by way of the port c³, and then passes from the port-chamber c² to the pipe A by way of the opening c⁴. The port-chest C is formed between the pipe-plates C' and partition-plates C² by means of the cross-partitions c c. These partitions are so arranged as to provide the ports c' and the port-chamber c² in their proper relations. The openings for the port c' are made through the pipe-plate C' and partition-plate C², and the port c³ and opening c⁴ are also provided in the plate C'.

This invention relates more particularly to the peculiar construction and relation of the air-chamber B, port-chest C, valves E, and pipes A.

The valve E is formed of a block e, which has provided in it the depression e'. The valve-leather e² is secured to the bottom face of the block, entirely covering the depression e'. These valve-blocks are fastened on the top of the plate C', each adjacent to the pipe which it controls. The valve-leather e² of the

valve E covers the ports c' c³. This arrangement of the valves on the top plate C' makes them readily accessible, and each valve can be independently removed and repaired when repairing becomes necessary. This arrangement, in connection with the port-chest C, is also particularly advantageous, because by means of this chamber the several ports can be readily constructed, all leading to the same register-chamber B.

I have provided the following mechanism for operating the valves E: When a register-stop is operated, air under pressure is admitted to the chamber B and passing into the ports c' exerts pressure on the valve-leather e². Normally an equal air-pressure is maintained above the valve-leather and this, by reason of the larger surface exposed above, readily seats the valve-leather and closes the valve E upon the port c'. Passing from the cavity or depression e' is an opening e³, which in the valve-block is preferably L-shaped, opening at the bottom of the block. Passages e⁴ are provided in the side plates of the port-chest and register-chambers, extending through the same and communicating with the channel-duct e⁶, arranged at the bottom of the register-chambers. The duct e⁶ connects the ducts e⁴ of the different registers in the system. An air-chamber F is placed conveniently to the pipe mechanism and has supplied to it constantly air under pressure. A duct e⁵ leads from the duct e⁴ into the port f, which port f communicates with the chamber F and also with the atmosphere. Valves f' and f² are arranged at the opposite ends of the port f on a stem f³. The stem f³ is carried by the upper block f⁴ of a bellows-motor F'. This bellows-motor is provided with the upper block f⁴, the flexible material, usually leather, f⁶, and a lower block f⁵. These are usually formed by simply cementing the leather around the outer peripheries of the blocks f⁴ and f⁵. The valves f' and f² are arranged a sufficient distance apart so that when one closes the port f the other of the said valves opens said port f. A duct F² leads from the bellows-motor F' to the key or pedal mechanism. An air-chamber G is provided near the key mechanism, in which is a valve g, which covers a port g², leading to the duct F². A spring g' assists the air-pressure in ac-

tuating the return movement of the valve g . A valve-pin g^4 extends from the valve g to the key or pedal H . The pedal H is pivoted so that a downward movement at the pedal 5 end operates the pedal-lever to raise the pin g^4 , and thus the valve g . As the valve g is raised the air passes through the port g^2 and duct F^2 to the bellows-motor F' . The effect of this is to close the valve f^2 and to open the 10 valve f' . Upon the opening of the valve f' the valve-leathers of the several valves in communication with said valves f' are immediately relieved of the air-pressure of the chamber F and the air from the chamber B 15 forces up the leather e^2 and immediately passes into the pipes. This action is almost instantaneous, as the valves E are opened immediately the valve f' is opened. A port g^3 communicates with the port g^2 and forms 20 a passage-way for the stem g^4 . A valve G' is arranged on this stem, so that as the pedal is operated to raise the stem g^4 and the valve g the valve G' closes the port g^3 , so that the communication with the atmosphere through 25 the port g^3 is cut off. When the key is relieved and the stem g^4 is lowered by the action of the valve g , the valve G' is opened and allows the air to escape from the bellows-motor F' . The bellows-motor has its upper 30 plate f^4 of larger area than the valve f^2 , so that immediately as the motor is relieved of internal pressure this greater area of the top plate f^4 , together with the toggle-joint effect of the leather f^6 under the action of the air, 35 operates to move the valve-stem f^3 and to thus close the valve f' and to open the valve f^2 . This places the depressions e' in communication with the air in the chamber F , and this pressure immediately forces the valve-leather e^2 down upon the port c' , thus closing 40 communication between the air-supply in the chamber B and the pipes.

What I claim as new is—

1. In a pipe-organ the combination with a 45 pipe; the pipe-plate in which said pipe is arranged; of a valve controlling said pipe, arranged to be removable from the side of said pipe-plate from which said pipe extends.

2. In a pipe-organ, the combination with a 50 pipe; and the pipe-plate in which said pipe is arranged; of the valve controlling said pipe located upon the side of said pipe-plate from which said pipe extends.

3. In a pipe-organ, the combination with the 55 pipes; the plate in which said pipes are arranged; of the valves controlling said pipes arranged upon the side of said plate from which said pipes extend, each valve immediately adjacent to the pipe which it controls.

4. In a pipe-organ, the combination with the 60 pipes, and the pipe-plate in which said pipes are arranged; of a series of independently-removable valves which are arranged to be removable from the side of said pipe-plate 65 from which said pipes extend.

5. In a pipe-organ, the combination with the

70 pipes; and the pipe-plate in which said pipes are arranged; of a series of independently-removable valves which are arranged upon the side of said pipe-plate from which said pipes extend, and which control the pipes.

6. In a pipe-organ, the combination with the 75 pipes arranged in the pipe-plate, C' ; of the air-chamber, B ; the port-chest, C , arranged between the air-chamber, B , and the pipe-plate, C' and valves on the pipe-plate controlling the ports in said port-chest.

7. In a pipe-organ, the combination with the 80 pipes; of the pipe-plate, C' ; the air-chamber, B ; the port-chest, C , arranged between the air-chamber and the plate, C' ; the partitions $c\ c'$, in said port-chest forming the ports, c' , and port-chambers, c^2 ; and the valves, E , arranged on the pipe-plate, C' .

8. In a pipe-organ, the combination of a 85 series of pipes of different registers; plates in which said pipes are arranged; air-ports leading from the different register-chambers to the pipes; valves arranged upon the sides of said pipe-plates from which the pipes extend 90 controlling the ports leading to the pipes.

9. In a pipe-organ, the combination with a 95 series of pipes of different registers; of pipe-plates in which said pipes are arranged; ports leading through said plates from the air-supply of each register; valves arranged upon said plates, and covering said ports, said valves being operated by air-pressure acting in opposition to the air-pressure in the ports leading to the pipes; ducts, e^4 , arranged in 100 communication with an air-supply controlled by the key mechanism and with said valves; and the channel-ducts, e^6 , connecting the several ducts, e^4 .

10. In a pipe-organ, the combination with 105 the pipes of different registers; of pipe-plates, C' , in which said pipes are arranged; an air-chamber, B , one for each register; a port-chamber, C , between the plates, C' , and the chamber, B , of each register, said port-chamber being provided with ports leading from the air-chambers through the pipe-plates and to the pipes; the valve, E , having the depression, e' , and valve-leather, e^2 , arranged over the ports leading from the port-chamber; the 110 ducts, e^4 , communicating with the depressions of the valves, E , and an air-supply controlled by the key mechanism; channel-ducts, e^6 , connecting the several ducts, e^4 ; and a key mechanism for controlling the air-pressure in the 115 ducts, e^4 .

11. In a pipe-organ, the combination with 120 the pipes of different registers; of pipe-plates, C' , in which said pipes are arranged; an air-chamber, B , one for each register; a port-chamber, C , between the plates, C' , and the chamber, B , of each register, said port-chamber being provided with ports leading from the air-chambers through the pipe-plate and to the pipe; the valve, E , having the depression, e' , and valve-leather, e^2 , arranged over 125 the ports leading from the port-chamber; the 130

ducts, e^4 , communicating with the depressions of the valves, E, and an air-supply controlled by the key mechanism; channel-ducts, e^6 , connecting the several ducts, e^4 ; the chamber, F; 5 a port leading from said chamber to the ducts, e^4 ; a valve composed of the members, f' and f^2 , one controlling the opening of said port to the atmosphere, and the other controlling the opening to the chamber, F; the stem, f^3 , 10 carrying said valve members and connected with the bellows-motor, F'; the bellows-motor, F'; a duct, F², leading from said bellows-motor and communicating with the air-chamber, G; the air-chamber, G; the valves, g, 15 controlling the communication between said

chamber, G, and the duct, F²; and a key mechanism for operating the valve, g.

12. In a pipe-organ, the combination with a pipe; a pipe-plate in which said pipe is arranged; of a valve arranged on said pipe-plate, 20 and adjacent to said pipe, said valve being formed of a block having the depression, e' , and a valve-leather, e^2 , and ports controlled by said valve.

In testimony whereof I affix my signature 25 in presence of two witnesses.

AUGUSTUS B. FELGEMAKER.
